CLAIM

We claim the ornamental design for a double-DIN auto stereo mounting device, as shown and described.

DESCRIPTION

FIG. 1 is a right front perspective view of a double-DIN auto stereo mounting device showing our new design;

FIG. 2 is a front elevation view of FIG. 1;

FIG. 3 is a top plan view of FIG. 1;

FIG. 4A is a right side elevation view of FIG. 1, the left side being a mirror image thereof;

FIG. 4B is a right side elevation in cross-section, along line 4B—4B of FIG. 2, to better illustrate certain features of the disclosed design;

FIG. 5 is a left side elevation view of FIG. 1;

FIG. 6 is a bottom plan view of FIG. 1; and,

FIG. 7 is a rear elevation view of FIG. 1.
